SPIKE EXTRACTOR

Filed June 8, 1928

UNITED STATES PATENT OFFICE

FRANCIS A. JIMERSON, OF ATHENS, PENNSYLVANIA, ASSIGNOR TO INGERSOLL-RAND COMPANY, OF JERSEY CITY, NEW JERSEY, A CORPORATION OF NEW JERSEY

SPIKE EXTRACTOR

Application filed June 8, 1928. Serial No. 283,896.

This invention relates to extracting devices, but more particularly to a spike extractor adapted for removing spikes from a tie or other article in which they are embedded.

One object of the invention is to facilitate the extraction of spikes from ties and similar articles.

Other objects will be in part obvious and in part pointed out hereinafter.

In the drawings accompanying the specification and in which similar reference characters refer to similar parts,

Figure 1 is an elevation partly in section, of a spike extractor constructed in accordance with the practice of the invention,

Figure 2 is a sectional elevation taken through Figure 1 on the line 2—2 looking in the direction indicated by the arrows, and

Figure 3 is a side elevation of the extracting elements, partly broken away, illustrating the manner in which the device may be located for extracting a spike.

Referring more particularly to the drawings, the invention comprises a frame A to which is secured a cylinder B by means of bolts C. The cylinder B is provided with a plunger D and has a removable end-head E threaded in this instance into the rearward end of the cylinder.

To opposite sides of the cylinder B are secured handles F and G for locating the extractor with respect to the work, such as a spike H seated in a tie J for securing a rail K thereto. The handle F may consist of a pipe or rod threaded into one side of the cylinder. The handle G in addition to its function as a handle preferably also serves as a means for controlling the admission of pressure fluid into the cylinder and the exhaust of fluid therefrom so that in effect it is also a throttle valve. For the sake of simplicity of illustration, the handle G is adapted to rotate relatively to the cylinder B and is held against endwise movement with respect thereto by means of a flanged nut L forming an abutment for a flange O carried by the handle.

Secured to the handle G is a connection P which conveys pressure fluid from a suitable

source of supply (not shown) to a passage Q in the handle G and which passage is adapted to register with passages R and S in the wall of the cylinder B and leading to the forward and rearward ends respectively of 55 said cylinder. The exhaust of fluid from the ends of the cylinder B is effected through a passage T in the handle G, said passage being adapted to communicate at one end with the passages R and S in the cylinder and at its 60 opposite end with the atmosphere. It is to be understood that the pressure fluid controlling feature of the handle G forms no part of the present invention. It is shown merely for illustrative purposes and any well 65 known throttling device which possesses the dual functions of a handle and a throttle valve may be utilized for this purpose.

The means adapted to engage the spike H for extracting it from the tie K consist of a 70 pair of jaws U and V pivoted together intermediate their ends by a pin W. The pin W is of such length as to receive on one end thereof a guide roller X adapted to roll in a guideway Y in one side of the frame A 75 for maintaining the jaws U and V in operative position. The guide roller X abuts in this instance with its inner end a washer Z adapted to slide on the inner surface of the frame A and is held in operative position by 80 a nut b threaded on the pin W, said nut also serving to clamp the jaws U and V together.

The gripping portions c of the jaws U and V are identical and are adapted to oscillate in the same plane. The jaws U and V differ 85 only with respect to the lever portions d and e of the jaws V and U respectively, the jaw V having two lever portions d and the jaws U one which, in the assembled position, lies between the lever portions d.

Suitable means are provided for actuating the jaws U and V to both the closed and open positions and for multiplying the force applied to the piston D for retracting the jaws 95 to extract the spike H from the tie. These means comprise two pairs of toggle links f and g which extend in opposite directions and are pivoted on a common pivot h supported by a coupling j. The coupling j is prefer- 100

ably threaded on a rod *k* secured at its uppermost end to the piston *D*.

The toggle links *f* and *g* are in all respects identical. The links *g* lie flush against each other and are interposed between the links *f*. Due to this arrangement, the links *g* may also extend between the lever portions *d* of the jaw *V* to which they are pivotally secured by means of a pin *o* carrying a roller *p* rotatable in arcuate slots *q* in the lowermost portion of the links *g*. The lever portion *e* of the jaw *U* is secured to the links *f* in a like manner. In this instance, however, the lever portion *e* extends between the links *f*, and the pin *o* whereby the lever portion *e* is connected to the links *f* carries a pair of rollers *r* disposed on opposite sides of the lever *e* to engage the arcuate slots *q* of the links *f*.

In order to enable the jaws *U* and *V* to be closed on the spike before the movement of the piston *D* becomes effective for exerting a pull on the jaws in a longitudinal direction, the slots *q* are of such conformation that the lowermost sides of the slots act as cam surfaces *s* which engage the rollers *p* and *r*. The curvature of the cam surfaces *s* is such that the longitudinal movement of the rod *k* will not, at the initial movement of the piston *D*, result in a similar movement of the jaws *U* and *V*. The movement of the cam surfaces *s* will merely result in closing the jaws *U* and *V* without imparting any longitudinal movement thereto.

In order to insure this closing effect of the jaws, the links *g* and *f* are provided with arms *t* at their uppermost surfaces to bear on fulcrums *u* supported in fixed position by the frame *A*. The fulcrums *u* preferably consist of rollers *w* disposed on pins *x* seated in the frame *A*.

The arms *t* extend generally in the direction of the cam surfaces *s* and serve to assure the proper movement of the cam surfaces *s* for closing the jaws and also act as levers for multiplying the force applied to the piston *D* for the purpose of overcoming great resistance such as is frequently encountered in loosening a spike from the tie.

To the end that the device may be readily maintained in the operative position and held against accidentally sliding on the article from which the spike is to be extracted, such as the tie *J* and the rail *K*, the frame *A* is provided with a pair of rail grips *y* which are secured to opposite sides of the frame *A* by means of screws *z*. The rail grips are preferably rigidly secured to the frame *A* and have serrated surfaces *2* at their lowermost ends to engage the article whereby the device is supported.

In order to maintain the rod *k* coaxial with the cylinder *B*, a guide block *3* may be disposed on the pin *h* to slide in the guideway *Y*. Preferably the block *3* is provided on its

outer end with a flange *A'* to engage the outer surface of the frame *A* adjacent the guideway *Y*.

The operation of the device is as follows: Whenever it is intended to remove a spike *H* from a tie *J*, the extractor is placed against the side of the rail *K* in the manner illustrated in Figures 2 and 3, it being assumed, of course, that the piston *D* is in its lowermost position to assure the open position of the jaws *U* and *V*. Pressure fluid is then admitted into the lowermost portion of the cylinder *B* to retract the piston *D*. As the piston *D* proceeds in an upwardly direction, the rod *k* will rock the links *g* and *f* about the fulcrums *u*. This movement of the links will cause the cam surfaces *s* to act on the ends of the lever portions *d* and *e* of the jaws and close the jaws on the spike *H*.

During this stage of the movement of the piston *D*, the movement of the links *g* and *f* will be effective only for imparting a lateral movement to the gripping portions *c* of the jaws. After the jaws *U* and *V* are closed on the spike *H*, further movement of the jaws in this direction will, of course, cease and from this point on the upward movement of the piston *D* will cause the links *g* and *f* to effect a lever action of the jaws *U* and *V* and as a result the jaw, together with the spike *H*, will follow the movement of the piston, although at a considerably slower speed.

Due to the combination lever and cam action of the links, the force applied to the jaws *D* will be greatly multiplied during the first stage of longitudinal movement of the jaws. This is desirable for the reason that it is at this stage of the operation of extracting a spike that the maximum resistance is encountered. Such maximum force may extend throughout a suitable portion of the extracting stroke of the piston to render the device applicable for use for extracting spikes from rails of different types in which, of course, the distance from the tie to the head of the spike varies.

When the jaws *U* and *V* have been retracted a sufficient distance to loosen the spike *H* from the tie the innermost portions of the links *g* and *f* will be elevated to such a point that the rollers *p* and *r* engage the ends of the arcuate slots of the links *g* and *f* thus preventing further rotation of the links about the pin *h* and the lever action of the links is no longer effective since then the arms *t* are raised above the fulcrums *u*. From this point only the force applied to the piston *D* will exert a pulling effect for raising the spike *H* from the tie.

After the spike *H* has been extracted, the handle *G* may be rotated to such a position that the passage *T* registers with the passage *R* for exhausting the pressure fluid from the front end of the cylinder. At the same time

the passage Q will register with the passage S for admitting pressure fluid into the uppermost end of the cylinder to again restore the piston and the extracting elements to their initial positions.

5 After the spike has been extracted from the tie J, said spike will remain between the jaws U and V during the entire upward or retracting stroke of the piston D as well as during a portion of the downward or return stroke of the piston. As the piston again approaches its initial position the arms t of the toggle links f and g will be engaged by the fulcrums u so that as the jaws U and V are lowered they will again be opened by the cam surfaces s. In this way the spike H will be automatically released from the jaws and the jaws will be in the open position in readiness for engaging another spike.

10 The present invention has been found to be unusually effective for extracting spikes from an article in which they are embedded. A spike may be readily and quickly removed with a minimum of manual effort and, owing 15 to the direct pull which the device exerts on the spike for extracting it, the spike will not be distorted and become unfit for repeated use as is the case with spikes removed by means of bars or hooks. Moreover, the extractor is adapted for use with all types of spikes regardless of form or size as the jaws U and V are adapted to exert the same gripping action in all cases.

I claim:

15 1. A spike extractor comprising a pair of jaws, a frame, pressure actuated means on the frame for retracting the jaws to extract a spike from an article in which it is embedded, and means pivotally connected to 20 said jaws and the pressure actuated means and adapted to act against the frame for first closing the jaws before the retracting movement of said pressure actuated means becomes effective for retracting the jaws.

25 2. A spike extractor comprising a frame, a cylinder on the frame provided with a piston, a rod on the piston, a pair of jaws adapted to grasp a spike, lever portions carried by the jaws, toggle links pivoted to the rod, and 30 cam surfaces on the toggle links acting against the lever portions for closing the jaws on a spike before the movement of the piston becomes effective for retracting the jaws.

35 3. A spike extractor comprising a frame having a guideway, a cylinder on the frame provided with a piston, a rod on the piston, a pair of jaws adapted to grasp a spike, lever portions carried by the jaws, toggle links pivoted to the rod, cam surfaces on the toggle links acting against the lever portions for closing the jaws on a spike before the movement of the piston becomes effective for retracting the jaws, and a block carried by the 40 rod extending into the guideway and inter-

lockingly engaging the frame for preventing transverse movement of the toggle links.

4. A spike extractor comprising spike engaging means, pressure actuated means for actuating said engaging means, link 70 means connecting the engaging means to the pressure actuated means, and means fixed relatively to the link means and forming abutments for the link means to multiply the force of the pressure actuated means during 75 the operation of dislodging a spike from an article in which it is embedded.

5. A spike extractor comprising a frame, a cylinder on the frame provided with a piston, a rod on the piston, means adapted to engage a spike, toggle links pivotally connected to the rod and said means, fulcrums on the frame, and arms on the links bearing on the fulcrums to multiply the force of the piston during the early portion of the stroke of the piston for dislodging a spike from an article 85 in which it is embedded.

6. A spike extractor comprising a frame, a cylinder on the frame provided with a piston, a rod on the piston, a pair of jaws adapted to 90 grasp a spike, toggle links pivotally connected to the rod and the jaws, cams on the toggle links for closing the jaws on a spike, fulcrums on the frame, and arms on the links bearing on the fulcrums to multiply the force 95 of the piston during the initial movement of the piston for dislodging a spike from an article in which it is embedded.

7. A spike extractor comprising a frame, a cylinder on the frame provided with a piston, a rod on the piston, jaws adapted to engage a spike, fulcrums on the frame, toggle means connecting said rod and said jaws and comprising cam and lever elements co-operating with said jaws and said fulcrums 100 to multiply the force exerted by the piston during a portion of its stroke for dislodging a spike from an article in which it is embedded.

8. A spike extractor comprising spike engaging means, a pressure actuated piston, integral cam and lever elements connecting said engaging means and said piston, and means forming abutments for the lever elements whereby the force transmitted by said 110 piston to said engaging means is multiplied for dislodging a spike from an article in which it is embedded.

9. A spike extractor comprising spike engaging means, a pressure actuated piston to 115 actuate the engaging means, integral cam and lever elements connecting said engaging means and said piston, and abutments arranged fixedly with respect to the lever elements and forming seats therefor to enable 120 the cams to multiply the force transmitted by said piston to said engaging means during a portion of the stroke of said piston.

10. A spike extractor comprising a frame, a cylinder on the frame provided with a pis- 130

ton, a rod on the piston, a pair of jaws adapted to grasp a spike, toggle links pivotally connected to the rod and the jaws, cams on the toggle links for closing the jaws on a spike, fulcrums on the frame, and arms on the links bearing on the fulcrums to multiply the force of the piston during the initial movement of the piston for dislodging a spike and to open the jaws for releasing the spike during the return stroke of the piston.

11. A spike extractor comprising a frame, a cylinder on the frame provided with a piston, a rod on the piston, a pair of jaws adapted to grasp a spike, toggle links pivotally connected to the rod and the jaws, cams on the toggle links for closing the jaws on a spike, fulcrums on the frame, and arms on the links bearing on the fulcrums to multiply the force of the piston during the initial movement of the piston for dislodging a spike and to open the jaws for releasing the spike as the piston approaches the end of its return stroke.

12. A spike extractor comprising a frame provided with fulcrums, a cylinder on the frame, a piston in the cylinder and carrying a rod, a pair of jaws adapted to grasp a spike, toggle links pivoted to the rod, cam surfaces on the toggle links, means associated with the jaws adapted to bear on the cam surfaces at points intermediate the rod and the fulcrums, and means on the toggle links adapted to bear against the fulcrums for multiplying the force exerted by the piston during a portion of the stroke of said piston for dislodging a spike from an article in which it is embedded.

13. A spike extractor comprising a frame provided with fulcrums, a cylinder on the frame, a piston in the cylinder and carrying a rod, toggle links pivoted to the rod, cam surfaces on the toggle links, a pair of jaws adapted to grasp a spike and having rearwardly extending lever portions, means on the lever portions for engaging the cam surfaces at points intermediate the rod and the fulcrums to pivotally secure the lever portions to the toggle links, and means on the toggle links adapted to bear against the fulcrums to multiply the force exerted by the piston during a portion of the stroke of said piston for dislodging a spike from an article in which it is embedded.

14. In testimony whereof I have signed this specification.

FRANCIS A. JIMERSON.
